UNITED STATES PATENT OFFICE.

JOHN F. WHITE, OF CHICAGO, ILLINOIS, ASSIGNOR TO WHITE PRODUCTS COMPANY, OF CHICAGO, ILLINOIS, A CORPORATION OF ILLINOIS.

HOOD LATCH.

Application filed April 4, 1921. Serial No. 456,124.

To all whom it may concern:

Be it known that I, JOHN F. WHITE, a citizen of the United States, residing at Chicago, in the county of Cook and State of Illinois, have invented certain new and useful Improvements in Hood Latches, of which the following is a specification.

This invention has as its object the provision of a latch which is particularly adapted for use as a hood fastening means in motor trucks and the like wherein the heavily constructed hoods of the same must necessarily be secured in their closed positions by proportionately strong yet readily manipulated means. Although, as specified, this latch is intended primarily for use with vehicles of more or less massive construction, it is however an excellent hood latch for pleasure cars, and an efficient latching means when used in other connections of a similar nature.

The general purpose of the invention is the provision of such a latch which is operated to fasten or unfasten by a compressive gripping action on the co-acting handles thereof, whereby the spring tension resisting said compression is readily manipulated without the necessity of the strenuous and inconvenient push or pull on the latch handle characterizing the fastening means ordinarily employed in this connection.

A further purpose is the provision of such a latch which presents a most pleasing and distinctive appearance, being formed to simulate, both in the manner in which it is grasped and in its shape, a pistol grip.

Other objects and advantages of the invention will be appreciated as the nature of the same is better understood from the following description when read upon the accompanying drawing. One embodiment of the invention has been chosen to set forth the novel construction and advantageous features of the same, but, inasmuch as it is evident that unessential details of the construction may be varied without departing from the spirit of the invention, it should be understood that this embodiment is not intended to restrict unnecessarily the scope of the appended claims.

In the drawing—

Fig. 1 is a side elevation of the latch, showing in section the adjacent portions of the vehicle hood and chassis;

Fig. 2 is a front elevation of the latch; and

Fig. 3 is a vertical longitudinal section through the same.

Referring in detail to the drawing let it be understood that the numeral 10 indicates the side of a vehicle hood which is hinged along its upper edge in order to swing outwardly and upwardly, 11 an adjacent portion of the vehicle chassis, and 12 a flanged member carried by the chassis to form an abutment for limiting the inward movement of the side 10 of the hood.

The latch of this invention, which is designated generally by the numeral 13, projects obliquely downward through a vertically elongated slot 14 in the side of the hood, and is pivotally mounted on a transverse pin 15 which is carried by the hood on the inner side thereof. The portion of the latch directly journaled on the pin 15 is an apertured ear 16 which is formed integral with and projects outwardly from a tubular guide barrel member 17 at a point intermediate the ends of the same. The upper outer tip of this ear is provided with a lip 18 which, when the latch as a unit pivots inwardly, abuts against the inner surface of the hood at the upper end of the slot 14 and thereby limits further pivotal movement of the latch in that direction.

A handle 19 is formed on the tubular member 17 at a point opposite the ear 16, and extends outwardly at right angles to the longitudinal axis of the member, being curved slightly downward at its outer extremity in order to provide a handle from the end of which there is no tendency for one's fingers to slip when grasping the same and exerting pressure thereon.

The lower end of the member 17 is closed except for a small circular aperture 20 formed concentric therewith through which the hooking member 21 slidably moves. That portion of the tubular member 17 above the ear 16 and handle 19 has telescoped thereover a relatively short tubular sleeve 22 adapted to slide longitudinally on said upper portion of the member 17. The sleeve 22 is closed at its upper end and has concentrically secured therein the upper extremity of a rod 23 which forms the shank of the previously mentioned hooking member 21. The lower end of this rod, ex-

teriorly of the bottom of the tubular member 17, is bent into a keeper-engaging hook 24.

A coiled spring 25 encompasses the shank 5 of the rod 23, and is confined between, and exerts continuous pressure against, the closed bottom of the member 17 and the closed top of the sleeve 22. The hook 24 limits the separation of said member and sleeve by 10 abutting against the bottom of the former. The two extremities of the spring are embedded, as shown at 26, in the closed ends of the tubular member and sleeve, whereby any accidentally imparted angular movement 15 of the sleeve relative to the member immediately serves to create a torque which will return the former to its previous normal position.

A laterally extending handle 27 is formed 20 on one side of the tubular sleeve 22 near the top thereof. This handle is similar to the handle 19 and is disposed parallel to, but spaced above, the same.

When the handles 19 and 27 are gripped 25 by the hand and drawn together the rod 22 will be projected downwardly against the tension of the spring 25, bringing the hook 24 into position to engage under a wide yoke portion 28 of a keeper 29 attached to 30 the vehicle chassis.

The operation of the latch is as follows: To fasten the same, assuming of course that the side of the hood is in the lowered position shown, it is only necessary to squeeze together 35 the handles 19 and 27, whereupon the hook 24 will ride under the keeper yoke 28. Merely pressing downwardly on the upper handle 27 will give substantially the same result but is not so easy inasmuch as it is often 40 inconvenient and awkward, when one is standing along side but spaced from the hood, to shift one's weight onto the handle, and it is furthermore a strain inwardly and downwardly on the hood at this point which is not produced when one by a squeezing action 45 counterbalances the forces used in compressing the spring 25.

To unfasten the latch one simply squeezes the handles thereof and accompanies this 50 compressive action with a slight upward and inward swing of the handles as a unit, whereby the hook is disengaged from the keeper yoke and moved outwardly away from the same. Due to the pivotal mounting 55 of the latch it will be understood that such a pivotal upward and inward swing of the handles naturally accompanies this compressive action. The latch, when circumstances demand it, may also be disengaged 60 by turning the upper handle to either side, whereupon the hook cams downwardly and becomes disengaged from the keeper yoke which is of a wide construction for this purpose; the previously mentioned torque created 65 by such an angular movement of the

tubular sleeve serving to return the handle subsequently to its normal position in parallelism with the lower handle 19.

I claim:

1. In a hood latch, a guiding member, a keeper, a keeper-engaging member adapted to move longitudinally of said guiding member and provided at its lower end with a hook, yieldable means tending to maintain said keeper-engaging member in the 70 position in its longitudinal movement most removed from the keeper, and cooperating handles associated with said keeper-engaging member and guiding member for moving the former relative to the latter against the 75 resistance of said means, said handles providing when thus moved a handle structure by means of which the movable hood structure mounting the latch may be moved outwardly and upwardly without releasing the 80 pressure of the yieldable means acting on the handles.

2. In a hood latch, a pivotally mounted guiding member, a keeper, a keeper-engaging member adapted to move longitudinally of said guiding member and provided at its lower end with a hook, yieldable means tending to maintain said keeper-engaging member in the position in its longitudinal movement most removed from the keeper, 90 and cooperating handles associated with said keeper-engaging member and guiding member for moving the former relative to the latter against the 95 resistance of said means.

3. In a hood latch, a pivotally mounted guiding member, a keeper, a keeper-engaging member adapted to move longitudinally of said guiding member and provided at its lower end with a hook, yieldable means tending to maintain said keeper-engaging member in the position in its longitudinal movement most removed from the keeper, and substantially parallel spaced handles associated with said keeper-engaging member and guiding member for moving the former relative to the latter against the 100 resistance of said means.

4. In a hood latch, a pivotally mounted guiding member, a keeper, a keeper-engaging member adapted to move longitudinally of said guiding member and provided at its lower end with a hook, yieldable means tending to maintain said keeper-engaging member in the position in its longitudinal movement most removed from the keeper, cooperating handles associated with said keeper-engaging member and guiding member for moving the former relative to the latter against the resistance of said means, and means associated with said guiding member for limiting the pivotal movement of the same.

5. In a hood latch, a pivotally mounted guiding member, a keeper, a keeper-engaging member adapted to move longitudinally 115

of said guiding member and provided at its lower end with a hook, yieldable means tending to maintain said keeper-engaging member in the position in its longitudinal movement most removed from the keeper, cooperating handles associated with said keeper-engaging member and guiding member for moving the former relative to the latter against the resistance of said means, and means associated with said guiding member for limiting the pivotal movement of the same, said means including a projection adapted to abut against a portion of the hood.

6. In a hood latch, a barrel portion, a keeper, a keeper-engaging member adapted to move longitudinally within said barrel portion and provided at its lower end with a hook, yieldable means tending to maintain said member in the position in its longitudinal movement most removed from the keeper, and cooperating handles associated with said member and barrel portion for moving the former relative to the latter against the resistance of said means, said handles providing when thus moved a handle structure by means of which the movable hood structure mounting the latch may be moved outwardly and upwardly without releasing the pressure of the yieldable means acting on the handles.

7. In a hood latch, a guiding member provided with a handle disposed at right angles thereto, a keeper, a keeper-engaging member adapted to move longitudinally of said guiding member in a direction oblique to the plane of the adjacent hood portion and provided adjacent its upper end with a handle disposed at right angles thereto and at its lower end with a hook, and yieldable means tending to maintain said keeper-engaging member in the position in its longitudinal movement most removed from the keeper.

8. In a hood latch, a guiding member provided with a handle disposed at right angles thereto, a keeper, a keeper-engaging member adapted to move longitudinally of said guiding member and provided adjacent its upper end with a handle disposed at right angles thereto and at its lower end with a hook, and yieldable means tending to maintain said keeper-engaging member in the position in its longitudinal movement most removed from the keeper, said means also tending to resist angular movement of the keeper-engaging member relative to the guiding member.

9. In a hood latch, a pivotally mounted tubular member provided with a handle disposed at right angles thereto, a keeper, a keeper-engaging member adapted to move longitudinally within said tubular member

and provided adjacent its upper end with a handle disposed at right angles thereto and at its lower end with a hook, and yieldable means tending to maintain said keeper-engaging member in the position in its longitudinal movement most removed from the keeper.

10. In a hood latch, a tubular portion provided at one side with a laterally extending handle, a sleeve member provided at one side with a laterally extending handle and telescoping over the upper end of said tubular portion in longitudinal sliding contact therewith, a keeper-engaging member carried by said sleeve and passing through the tubular member, a keeper, a coil spring encompassing said keeper-engaging member and acting longitudinally at one end against said tubular portion and at the other end against said sleeve member.

11. In a hood latch, a pivotally mounted tubular portion provided at one side with a laterally extending handle, a sleeve member provided at one side with a laterally extending handle and telescoping over the upper end of said tubular portion in longitudinal sliding contact therewith, a keeper-engaging member carried by said sleeve and passing through the tubular member, a keeper, a coil spring encompassing said keeper-engaging member and acting longitudinally at one end against said tubular portion and at the other end against said sleeve member.

12. The combination with the keeper and hood, of a latch member provided with a hook for engaging the keeper, a latch guide carried by the hood, a spring acting upon the latch in a direction opposed to the keeper, and juxtaposed handles carried by the guide and latch for compressing the spring and engaging the hook with the keeper, one of said handles being movable in a direction oblique to the plane of the adjacent hood portion.

13. The combination with the keeper and hood, of a latch member provided with a hook for engaging the keeper, a latch guide pivotally carried by the hood, a spring acting upon the latch in a direction opposed to the keeper, and juxtaposed handles carried by the guide and latch for compressing the spring and engaging the hook with the keeper.

In testimony whereof I have hereunto signed my name in the presence of two subscribing witnesses.

JOHN F. WHITE.
